UNITED STATES PATENT OFFICE.

ORLAND F. BAUGHMAN AND JOSEPH HABART, OF LAKEWOOD, OHIO, ASSIGNEES TO
THE BANKERS SAVINGS & CREDIT SYSTEM COMPANY, OF CLEVELAND, OHIO, A
CORPORATION OF OHIO.

MONEY BANK.

Application filed May 11, 1925. Serial No. 29,394.

This invention relates to improvements in that class of money banks or receptacles that are used by banking institutions for distribution among the patrons of their savings accounts to encourage the saving of small amounts at convenient times, such amounts being placed within the money banks or receptacles and when a sufficient sum has been accumulated therein to warrant the trouble, or at such times as the patron finds it desirable, the money bank or receptacle is taken to the bank and presented to the receiving teller, who holds the key to the bank, and he removes the contents and places it to the credit of the patron.

While it is desirable to make money receptacles of the kind in question ornamental in appearance and large enough to attract attention and prevent its becoming too easily misplaced or concealed by other objects, it is, on the other hand, convenient to have the money container small enough to be easily carried in a pocket or in a lady's hand bag.

It is the purpose of our invention to accomplish both the foregoing desirable results by providing a bank that is ornamental in appearance and large enough to properly serve its purpose, and which incorporates a readily removable coin or money container that is of such size and character that it may be conveniently carried to the savings bank for the purpose of depositing its contents.

To this end we provide a casing that may be made in any suitable shape and rendered ornamental by artistic design or embellishments and to place within the casing a coin or money receptacle that is provided with the usual coin slot and lock and connected to the casing in such way that it may be readily removed therefrom.

In the present embodiment of our invention we have made the casing in the general shape of the Liberty Bell, and the removable money receptacle is designed to occupy the cavity of the bell and to be inserted from the bottom thereof. Obviously the casing may be made in any desired shape that is appropriate for the purpose, and the money receptacle of a size and design to suit the shape of the casing, or, if desired, the receptacle may be made collapsible, as in part of

leather or fabric, so that it will fit compactly within the pocket or hand bag.

In the accompanying drawing, Fig. 1 is a central vertical section through the money bank; Fig. 2 is a bottom plan view of the same; Fig. 3 is a central vertical section through the casing and shows the money receptacle in elevation and as partly withdrawn from the casing; and Figs. 4 and 5 are enlarged sectional details on the respective lines 4-4 and 5-5 of Fig. 2.

The casing is designated 1, and, as previously stated, it is designed to resemble the Liberty Bell; and secured to its upper end by means of a stamped metal fitting 2 is a member 3 in representation of the bell supporting beam. Fitted within the downwardly diverging flange 5 that surrounds the open end of the casing is the peripheral flange 6 of an annular bottom 7, the edge portion of the flange 5 being peened over the edge of the flange 6, as indicated at 8, for holding the bottom in place. Inward displacement of the bottom 7 is prevented by the upwardly converging wall of the casing.

Within the casing 1 is a money receptacle 10 and a ring 11 that is angular in cross-section is fitted into the lower end of the receptacle in the same manner that the bottom 7 is fitted within the lower end of the casing 1, the ring 11 being held in place by the peened over edged portion 12 of the receptacle.

A closure 15 is designed to occupy the open end of the receptacle 10 and its peripheral flange 16 is spaced from its body portion by a cylindrical flange 17, the flange 17 being made to fit within the correspondingly shaped flange of the ring 11. Secured to one side of the closure 15 is a lug 18 that is arranged for engagement with the inner side of the ring 11, and carried by the closure at a point diametrically opposite the lug 18 is a lock 19 whose bolt 20 is also arranged to engage the inner side of the ring 11, the closure being thus held in place until the bolt 20 is retracted by a key that may be inserted through a key-hole 21 in the closure. The closure is provided with a coin or money slot 24 that is equipped with a suitable guard

designated 25. This guard constitutes no part of the present invention and a detailed description of it is therefore deemed unnecessary.

- 5 At points spaced apart circumferentially of the bottom 7—as at diametrically opposed points—the edge of said bottom, adjacent the opening through which the money receptacle is inserted, is slit radially and the 10 material adjoining each slit is depressed to form an arcuate socket 28. The peripheral flange 16 of the closure 15 is provided with notches 29 which are of sufficient circumferential extent to receive through them the 15 sockets 28, and when the receptacle is inserted into the casing, with the flange 16 engaging the bottom 7 and the sockets 28 extending through the notches 29, and the receptacle is turned in the proper direction— 20 as in a clockwise direction in the present instance—the portions of the flange 16 to one side of the notches 29 will enter the sockets 28 and thus hold the receptacle within the casing. As shown in Fig. 5, the 25 central portion of each of the sockets 28 is bulged upwardly so that the parts will be placed slightly under tension as the flange 16 is cammed beneath the overhanging walls of the sockets.
- 30 The manner of using the device is evident from the foregoing description.
- Having thus described our invention, what we claim is:—
1. In combination, a casing having a wall 35 provided with a comparatively large opening, a money receptacle that is adapted to be inserted into the casing through said opening, said receptacle also having an opening, a closure removably secured within the open- 40 ing of the receptacle and having a peripheral

portion overlying said wall of the casing about the opening thereof, said wall and said closure having on the one hand, sockets, and on the other parts designed to enter said sockets when the receptacle is rotated 45 with respect to the casing.

2. In combination, a casing having a bottom provided with a comparatively large opening, a money receptacle that is adapted to be inserted into the casing and having an 50 open bottom arranged to fit within the opening in the bottom of the casing, a closure removably secured within the open bottom of the receptacle and having a peripheral flange 55 overlying the bottom of the casing, said bottom having sockets adjacent the edge of said opening, and said flange having parts adapted to enter said sockets when the receptacle is rotated with respect to the casing.

3. In combination, a casing having a bottom provided with a comparatively large opening, a money receptacle that is adapted to be inserted into the casing and having an open bottom arranged to fit within the opening in the bottom of the casing, a closure 60 removably secured within the open bottom of the receptacle and having a peripheral flange overlying the bottom of the casing, said bottom having sockets adjacent the 65 edge of said opening, and the flange having parts adapted to enter said sockets when the receptacle is rotated with respect to the casing, the entering parts and sockets being so designed as to cause a binding between said parts as they are moved to holding position. 75

In testimony whereof, we hereunto affix our signatures.

ORLAND F. BAUGHMAN.
